UNITED STATES PATENT OFFICE.

ALFRED HEALD, OF PHILADELPHIA, PENNSYLVANIA, ASSIGNOR TO
McCALLUM, CREASE & SLOAN, OF SAME PLACE.

DESIGN FOR CARPET.

Specification forming part of Design No. 6,717, dated June 24, 1873; application filed June 6, 1873.

To all whom it may concern:

Be it known that I, ALFRED HEALD, of the city and county of Philadelphia, State of Pennsylvania, have invented a Design for a Carpet-Pattern, (E,) of which the following is a specification:

The figure in the accompanying drawing fully represents my design for a carpet-pattern, the remainder being merely a repetition of that which appears.

The principal feature of the design is the figure or member A, which has an irregular outline of the most elaborate character, composed principally of curved lines, there being also within the figure an elaborate central ornament, a. In the spaces between the figures A are smaller figures, B, of the character rep-

resented, and the groundwork between the several figures is occupied by foliated ornamentation, the nature of which is so clearly shown in the drawing as to require no minute description.

Irrespective of the colors employed, I claim—

The design for a carpet-pattern, substantially as described, and as represented in and by the accompanying drawing.

In testimony whereof I have signed my name to this specification in the presence of two subscribing witnesses.

ALFRED HEALD.
